UNITED STATES PATENT OFFICE

FRED WALSLEBEN, OF ROCKVILLE CENTER, NEW YORK, ASSIGNOR TO UNDERWOOD
ELLIOTT FISHER COMPANY, OF NEW YORK, N. Y., A CORPORATION OF DELAWARE

TYPEWRITING MACHINE

Application filed July 6, 1928. Serial No. 290,775.

This invention relates to a universal variable line-spacing mechanism for a typewriter-platen in which the unit of line-space distance may be micrometrically varied and in which different settings may be made for spacing predetermined multiples of said unit.

An object of the invention is to provide an efficient and compact mechanism for the type of machine in which the platen is mounted in a case-shifting frame or equivalent device, and which frame or device is carried by the usual letter-feeding carriage and is shiftable relatively to said carriage. A manually-operable reciprocatory line-space operator, preferably a lever mounted upon the letter-feeding carriage, is employed and the mechanism connecting said reciprocatory lever to the platen is organized so that the possibility of lost motion and binding of the line-spacing mechanism between the lever and platen, largely due to the non-rigid manner in which the case-shifting frame may be supported, is substantially minimized. The mechanism is further organized so that the force of its reaction upon the platen-frame is negligible and hence does not tend to twist said platen-frame or dislodge it from its bearings.

To these and other ends, the mechanism is organized so that all of its controlling parts are carried by, and are solidly supported by the letter-feeding carriage as distinguished from the heretofore-observed practice of mounting some, if not all, of such controlling parts upon the weakly supported platen-frame. A clutch and controlling device therefor, whereby only the advance movement of the reciprocatory line-space lever is effective to rotate the platen, are employed and constitute controlling parts of the mechanism. In the novel organization it is contrived to solidly support said clutch and its controlling device upon the letter-feeding carriage.

A form of clutch in which teeth interlock when said clutch is engaged, is preferably employed and on account of the aliquant relation between the clutch-tooth spacing and the variable line spacing to be effected, a fine

clutch-tooth pitch is employed, and the clutch is made to operate through a considerably larger degree of rotation than the required line-space rotation of the platen, so that the tooth line of the clutch has a correspondingly large displacement.

It will be readily understood that the large displacement of the clutch-tooth line, in conjunction with the fine clutch-tooth pitch, renders the aforesaid aliquant relation of the clutch-tooth pitch to the line spacing negligible and thus the uniformity of said line spacing is practically unimpaired. The driven side of the clutch may be connected to a rotary platen-driver preferably in the form of a gear whose axis extends substantially parallel to the direction in which the platen-frame is moved for case shifting. As will be shown, said platen driver or gear may, in the simplest disposal thereof, be directly connected to the driven member of the clutch and thus form part of said driven member. Means whereby the clutch is speeded up may also be solidly supported on the carriage-frame.

For compactness of the mechanism, the clutch and the platen driver or gear may be mounted coaxially with the line-space lever preferably upon an extension of the fulcrum of said lever. For speeding up the clutch and platen-driver, a pinion connected to the driving side of the clutch may mesh with a reciprocatory sector which may be operatively connected to the line-space lever by a link having one end pivotally connected to an arm of the sector, the other end of the link being connected to an arm of the line-space lever. The relative proportions of the sector and pinion meshing therewith may be such as to secure the desired large angular displacement of the clutch as compared to the usually limited angular displacement of the line-space lever.

Means may be provided for micrometrically varying either the length of the link-arm of the line-space lever or the length of the link-arm of the aforesaid sector. In the illustrated and preferred form of the invention it is the length of the line-space lever-arm that is thus varied, and by so varying said length,

the extent of line spacing resulting from a given movement of the line-space lever is correspondingly varied.

The rotary platen driver or gear has the same large rotary displacement as the clutch, and may be connected to the platen by a train of reducing gearing which may be retained in a mounting or fixture which may bear upon, or be otherwise centered by, said platen-axle to which one end of said train is keyed.

In its simplest form said train, which serves to translate the large rotation of the platen-driver into platen rotation of line-space extent, may consist of a bevel gear keyed to the platen-axle and meshing with a substantially smaller bevel pinion, said latter pinion being compounded with a substantially larger gear that may mesh with the platen driver or gear on the letter-feeding carriage.

The mechanism may be organized so that the direction of the reaction of the platen-driving gear, supported by the letter-feeding carriage upon the meshing gear of the reducing train carried by the platen-frame, is in a direction substantially longitudinal of the carriage and platen-frame. It will be understood, inasmuch as the displacement, at the point where the platen-driving gear on the letter-feeding carriage meshes with the large gear of the reducing train, is large as compared with the required extent of platen-rotation, that the force of reaction upon the platen-frame is correspondingly small; that is to say, the force of said reaction being inversely proportional to the displacement of the driving teeth of the platen-driver, it follows that the greater the displacement of said platen-driving gear-teeth the less will be the reaction upon the platen-frame. Consequently the angular displacement and the diameter of the platen-driving gear on the letter-feeding carriage are made as large as is compatible with the general design of the mechanism. This large angular displacement of the platen-driving gear is conveniently afforded by reason of direct connection of said latter gear to the aforesaid clutch which, as stated, also has a large angular displacement.

By suitable elongation of teeth, the platen-driving gear on the letter-feeding carriage may always engage the gear on the platen-frame meshing therewith, irrespective of the case-shift position of said platen-frame, it being understood that the teeth of said latter gear may be parallel to the teeth of the platen-driving gear which extend parallel to the direction in which the platen-frame is shifted.

A multiple space stop is provided to secure different multiples of the micrometrically variable line-space unit. Said stop may be in the form of an arm fulcrumed on the line-space-lever fulcrum. A segment having slots, notches or other suitable formations, located to establish the different stations, may be provided to hold the multiple space stop-arm,

which accordingly may have a portion which may be set into said slots, notches or formations.

The line-space multiple desired is determined preferably by controlling the extent of movement of the line-space lever, and accordingly the stop-arm may have a stop abutment for said line-space lever. The stop-arm, as will be shown, has provision which is novel in its simplicity and effectiveness for retaining it at its different stations, said provision also permitting ready release of the stop-arm preparatory to shifting it to a new position.

An important feature of the invention is that aside from the train of reducing gearing carried by the platen frame, all the other parts, including the controlling parts, of the mechanism, may be assembled in a compact and complete suit which may be readily attached to, or removed from, the letter-feeding carriage. By organizing the mechanism into such complete unit, proper adjustment of the mechanism is easily maintained and may be made as part of a factory organized process, so that all that is necessary in case the mechanism has to be supplied to a machine already in service, is to attach the unit by screws to the frame of the letter-feeding carriage. Similarly, the train of reducing gearing and the mounting or fixture therefor, may be assembled as a unit which may be readily slipped onto the platen-axle and may be provided with a portion which may serve to anchor said fixture or mounting to a suitable part of the platen-frame.

Where the novel organization is incorporated in two such separate and complete units, the only adjustment to be made in attaching said units to a typewriter is to secure proper meshing of the platen-driving gear of the one unit attached to the letter-feeding carriage with the mating gear of the reducing-train unit attached to the platen-frame or axle, and such adjustment for proper meshing is easily made, as will be seen later.

Each unit may be covered by a casing that serves as a protective covering and conduces to neat appearance. The casing of the main unit on the letter-feeding carriage may be formed to expose the handle of the line-space lever and other parts which are to be manipulated for adjusting the line-space distance. Said latter casing may also be formed to expose the portion of the platen-driving gear which engages the mating gear of the reducing train.

The platen-frame unit, including the train of reducing gearing, may be provided with a rotatable finger-knob disposed for easy access thereto and connected to the reducing train in such manner that it has a large angular displacement as compared with platen-rotation effected by manipulating said finger-knob. Thus said finger-knob may serve

for fine adjustment of a work-sheet on the platen to the printing line.

This invention is in the nature of an improvement upon the invention disclosed in the application of B. C. Stickney, Serial No. 137,948, filed September 27, 1926; no claims being made herein that cover the inventions of said Stickney.

Other features and advantages will hereinafter appear.

In the accompanying drawings,

Figure 1 is a top plan view, showing the relative positions of the parts of the mechanism, and showing the mechanism set for maximum spacing.

Figure 2 is a side elevation of the mechanism, some of the parts being shown broken away and in section.

Figure 3 is a top plan view of the mechanism, showing the reciprocating line-space operator or lever at the end of its line-spacing stroke, and also showing details not shown in the top plan view of Figure 1.

Figure 4 is a side elevation of the mechanism similar to Figure 2, and showing details not brought out in Figure 2.

Figure 5 is a top plan view of the mechanism similar to Figures 1 and 3, showing details not brought out in said latter figures. Figure 5 also indicates the mechanism as set for double spacing of a line-space unit of minimum extent.

Figure 6 is a side elevation of the mechanism, showing details of the casings enclosing the mechanism.

Figure 7 is a front elevation of the unit attached to the letter-feeding carriage, and illustrates further details of the casing enclosing said unit.

Figure 8 is a side elevation, showing the multiple line-space-lever stop withdrawn from a holding notch preparatory to shifting it to another position.

Figure 9 includes several views of details of means for controlling engagement and disengagement of the clutch.

Figure 10 is a top plan view of a mounting for the unit that is attached to the letter-feeding carriage.

Figure 11 is a rear elevation, showing details of the reducing gear train and its mounting, and the relation thereof in respect to the platen-frame and platen-axle; the view in this figure extending longitudinally of the platen-axle.

Figure 12 is a side elevation of the mounting shown in Figure 10.

Figure 13 shows, in perspective, the mounting for the aforesaid reducing gear train carried by the platen-frame.

Figure 14 is a perspective diagram of the mechanism as seen from the front of the letter-feeding carriage.

The novel line-spacing organization is herein illustrated as adapted for the well-

known Underwood typewriter, in which a revoluble platen 20 is secured to a platen-axle 21 journaled in end members of the usual platen-frame. Said platen-frame is herein represented by the left-end frame-member 22 thereof and moves up and down relatively to a letter-feeding carriage-frame 23 by means of the usual case-shifting devices, not shown. Of said carriage-frame there is shown only the forward and left end portion which supports the mechanism of the invention.

A reciprocating line-space lever, generally designated by the number 25, is best made in two parts, one part of a metal stamping 26, in which are embodied the fulcrum end and variable arm of the lever, and the other part a molded handle 27 which may be secured to said stamping by rivets 28. (Figure 3). The stamping 26 has formed therein a slot 29 in which a slide 30, having retaining grooves 31 closely fitting the sides of said slot, may serve to shift a pin 31 nearer to or further away from the fulcrum of the lever. Thus, for varying the line-space distance said lever is provided with an arm of variable length determined by the position of the pin 31, and for a given movement of the line-space lever the displacement of the pin 31, and consequently the line-space distance, depends on the distance of said pin 31 from the fulcrum 95 of the lever. Means for micrometrically varying said distance will be described later.

A clutch, which will be described, is employed in order that only the advance stroke of the line-space lever 25 is effective to rotate the platen, said clutch serving to complete operative connection between said line-space lever and the platen by and during the advance stroke of the lever, and conversely serving to permit the reverse stroke of said lever 105 to take place without reversing the platen. The clutch also serves to keep the connection between the line-space lever and the platen normally open in order that the platen may as usual be independently rotated. The driving side of the clutch is keyed to the line-space lever and the driven side of the clutch is keyed to the platen, and the manner in which the driven side of the clutch is keyed to the platen will be explained further on. For 115 line-space uniformity, governed by reasons which will become apparent, the clutch operates through a substantially larger degree of rotation than the required line-space rotation of the platen. Means whereby the driving 120 side of the clutch is keyed to the line-space lever and whereby the clutch is speeded up will now be described. The variable arm of the line-space lever, which may be regarded as terminating in the pin 31, is connected by 125 means of a link 32 to an arm 34 of a reciprocating gear-sector 35, one end of said link fitting over the pin 31, the other end of the link being pivotally connected at 33 to said arm 34. The gear-sector 35 meshes with a pinion

36 to which may be secured an arm 37, on the outer end of which there may be pivotally mounted a pawl 38 to form the driving side of the clutch. The driven side of the clutch is 5 embodied in a ratchet-wheel 39 which said pawl may engage. The teeth of the pawl and ratchet-wheel are made fine, and the diameter of the ratchet-wheel is made as large as is compatible with the general design of the 10 mechanism. Thus by reason of said fine tooth pitch, large diameter of the ratchet-wheel and large rotary displacement of the clutch, the aliquant relation of the clutch-tooth-spacing to line-spacing of the platen is negligible, 15 and does not impair uniformity of said line-spacing.

The ratchet-wheel side of the clutch is keyed to the platen by a connecting train which includes a rotary platen driver in the 20 form of a gear 40 which may be secured to the ratchet-wheel, as indicated in Figure 2.

To permit independent rotation of the ratchet-wheel and consequently of the platen, the pawl is normally disconnected from the 25 ratchet-wheel, as shown in Figure 1, and becomes connected to the ratchet-wheel by and during a small initial portion of the line-space-lever advance stroke. In order to avoid reversing the platen during the reverse 30 stroke of said lever, the pawl is preferably fully withdrawn from the ratchet-wheel by and during a small initial portion of said reverse stroke, that is to say, although the shape of the teeth of said pawl and ratchet-wheel 35 may be such that the pawl may drag idly over the ratchet-wheel-teeth during the reverse stroke, it is desirable, in order to avoid the wear attending such dragging of the pawl, that the latter be fully withdrawn from the ratchet-wheel as the reverse stroke is 40 begun. To this end, the pawl may be provided with an arm 42, which, as best shown in Figure 3, may be slotted to embrace a tab 43 of a ring 44 mounted for rotation about an axis concentric with the axis about which the pawl revolves. To enable said ring 44 and its tab 43 to co-operate with the pawl to effect engagement and disengagement of the latter, said ring is frictionally controlled, 45 and to this end, as best shown in Figure 9, is retained in a friction bearing, generally indicated by the number 47.

It will be seen from Figure 1 that a small initial movement of the pawl-carrying arm 55 37 in line-spacing direction will cause the pawl to be rotated relatively to said arm 37 by reason of the frictional drag on the ring 44, which furnishes the necessary reaction that effects said relative rotation of the pawl 60 and causes it to approach and engage the ratchet-wheel in said small initial movement. In the continued rotation of the now engaged pawl and ratchet-wheel, the ring 44 is constrained to rotate with said pawl and ratchet-wheel, and thus is, at the end of the line-space

stroke, in position to be effective to cause the pawl to recede from the ratchet-wheel during a small initial portion of the reverse movement of the pawl-arm 37.

The extent to which the pawl recedes from the ratchet-wheel may be just enough to enable the pawl, in its reverse stroke, to clear said ratchet-wheel and may be determined by means of a stop 41 projecting from the pawl-carrying arm 37. As said pawl-carrying arm 37 commences its reverse movement, the pawl recedes until the side of the arm 42 thereof strikes said stop 41. By reason of the frictional drag on the ring 44, the pawl is held against said stop throughout said reverse movement, and it will be apparent that said pawl remains disengaged after the reverse movement is terminated, so that the ratchet-wheel may be free to be rotated in any direction for independent rotation of the 85 platen.

A feature of the invention conducing to compactness of the mechanism, and other advantages, is the organization of the parts, whereby the clutch, that is to say the pawl-arm and ratchet-wheel, are mounted concentrically with the line-space-lever fulcrum. A stud, generally indicated by the number 45, may serve as a journal, around which the clutch and platen-driving gear 40 may freely rotate and may also serve as a fulcrum for the line-space lever 25.

The line-space lever 25, the clutch, platen-driving gear 40, and the other connections between said lever and driving-gear, may be 100 organized and assembled in a compact and complete unit ready for use, which may be secured to the letter-feeding carriage-frame. One form of a mounting suitable for the parts of such a unit is shown in detail in Figures 105 10 and 12, and may consist of an upper plate generally designated by the number 48, which may rest upon suitable seats 49 of the carriage-frame 23, and may be secured to the latter by screws 50. The mounting generally indicated by the number 46 carries the clutch and line-space-lever stud 45, which stud, for compacting the mechanism, may be lowered and hence may project from a lowered portion of the mounting. Said lowered portion may be a plate 51 spaced from the plate 48 by studs 52 which may also serve to fasten said plates 48 and 51 together, as indicated in Figure 12. The upper plate 48 may also carry a fulcrum stud 53 for the gear-sector 35.

The platen driver or gear 40 of the organization, supported by the carriage, frame 23 and rotated through a substantially larger degree of rotation than the required line-space rotation of the platen, may drive the platen through a reducing gear-train. Said train may include a gear 55 meshing with said gear 40, and compounded with a bevel pinion 56 meshing with and driving a bevel gear 57, the latter gear being keyed to the 125 130

platens-axle 21. The gear 55 and bevel pinion 56 may be secured one to the other and keyed to a spindle 58 which extends vertically or parallel to the axis of the gear 40, and is 5 journaled in a mounting generally indicated by the number 60.

The reducing gear-train from the gear 40 to the platen-axle 21 is retained and secured in proper operating position by said mounting, said gear-train and mounting moving up and down with the platen-frame during case shifting. In order that the gear 55 may be in mesh with the gear 40, irrespective of the case-shift position of the platen-frame, 10 the gear 40 may be elongated, as indicated in Figures 2 and 4. Figure 2 shows the relative positions of the gear 55 on the platen-frame and the platen-driving gear 40 on the carriage 23 when the platen-frame is in lower-case position. In Figure 4 the relative positions of 15 the gear 55 and gear 40, when the platen-frame is in upper-case position, are indicated by the full lines representing said gear 55, the lower-case position of said gear 55 being 20 represented by dot-and-dash lines in said Figure 4. In Figure 4 other parts of the platen-frame are shown in upper-case and lower-case positions, respectively, by full lines and dot-and-dash lines, as is clearly evident. 25

Because rotation of the platen as derived from operation of the line-spacing mechanism is variable, the teeth of the pawl and ratchet-wheel will not always be in alignment for direct engagement. It is for this reason that the ratchet-wheel and pawl move through the aforesaid greater rotation as compared with the rotation of the line-space lever and the required line-space rotation of 30 the platen, and it will be evident that by reason of this greater rotation the comparatively large diameter of the ratchet-wheel and the fineness of the ratchet-wheel and pawl teeth, that the effect of the aliquant relation between the line-spacing and the spacing of the 35 clutch-teeth is negligible, and hence does not practically impair the uniformity of the line-spacing.

It will be seen that it takes comparatively little effort to rotate the platen when said effort is applied at the teeth of the gear 55, inasmuch as due to the ratio of the reducing train of which said gear 55 forms a part, the teeth of said gear 55 have a large displacement as compared with the displacement of the platen effected by rotating said gear 55. Thus the mechanism on the carriage-frame, as the platen-driving gear 40 thereof rotates the gear 55, reacts with very little force upon 40 the platen-frame and the platen-frame is therefore not subjected to any undue twisting strain, nor does the platen-rotating effort, applied at the teeth of the gear 55, tend to dislodge the platen-frame from its bearings or supports. Moreover, the direction in which

the effort to rotate the gear 55 is applied is substantially longitudinal of the platen. An effort applied in such direction has the least tendency to twist or dislodge the platen-frame because the bearings or supports for the platen-frame are usually at the ends thereof, and, being thus spread apart in respect to the direction of said effort, afford more stable reaction than if said effort were to be applied transversely of the platen and its line of bearings. 70

The pin 31, which forms one extremity of the variable platen-driving arm of the line-space lever, may be shifted to vary the length of said arm by means of a spiral cam-groove 80 61, the sides of which may embrace said pin 31 which may be extended for this purpose. Said spiral cam-groove may be formed in a member 62 rotatable concentrically with the platen-lever fulcrum to effect adjustment of 85 the position of the pin. Said cam-groove-member 62 forms a part of the line-space lever 25, that is to say, it is rotatable therewith, so that the position of the pin 31 may not be disturbed. To retain said cam-groove-member 62, and at the same time furnish an adequate extent of bearing of the line-space lever upon its fulcrum-stud 45, there may be secured to said lever a sleeve or hub 63 having a hole which fits a reduced portion 64 of 90 said stud 45, said portion being reduced to afford a shoulder 65 upon which a flange 66 of said sleeve may rest to support the line-space lever at the proper level, and definitely separate it from the pawl-carrying arm 37 95 and the pinion 36 secured thereto. Said pawl-carrying arm may be fitted over a hub 67 of said pinion, and may be keyed to the pinion by a dowel 68, Figure 2, said hub 67 also serving to space said arm and pinion in 100 proper relation to associated parts of the mechanism, and to this end, may rest upon the upper surface of the friction-bearing 47 which retains the pawl-controlling friction ring 44. 105

For retaining the cam-groove-member 62, and also for affording an annular space in which a line-space-lever retracting-spring 69 may be placed, the line-space-lever sleeve 63 may be provided, at a point slightly below the 110 top of the cam-groove-member 62, with a flange 70 which fits a central hole 71 of said cam-groove-member so that the sides of said hole and of the sleeve may afford said annular space, as is indicated in Figure 2. The end 115 portion of said sleeve 63 may be threaded for a clamping nut 72 whereby the cam-groove-member 62 may be secured in any of its adjusted positions. The cam-groove-member 62 may be spaced at the proper level above 120 the top surface of the stamping 26 by tabs 73, preferably three in number, projecting upwardly from said stamping, said tabs being located to support the cam-groove-member 62 near the outer rim of the latter, in 125 130

order to clear the cam-groove and to co-operate most efficiently with the clamping nut 72 in holding said cam-groove-member.

For convenience of adjusting the tension 5 of the line-space-lever retracting-spring 69, the flange 70 may be provided with several notches 74, in any one of which the upper end 75 of the spring 69 may be held and retained. The spring 69 may be provided at 10 its lower end with an outwardly-extended portion 76 to react against the upper end of a stud 77 secured to, and projecting upwardly from, the plate 48 of the mounting 46 which supports the mechanism. Said stud 77 may 15 have a groove 78 to retain the spring end-portion 76. The upper end of the line-space-lever fulcrum-stud 45 may be threaded to receive a lever-retaining screw 80, the head of which may overlap the diameter of the sleeve 20 63 to serve as a stop for preventing undue loosening of the clamping nut 72, the top of the stud 45 extending sufficiently above the top of the sleeve 63 so that the head of said screw 80 does not bind upon said sleeve. 25 The friction-bearing 47, which retains the pawl-controlling ring 44, may be secured by being forced over a portion 81 of the stud 45 upon which the pawl-arm 37 and its pinion 36 rotate, and may be seated against a shoulder 30 82 of said stud 45 formed by an enlarged portion 83 of the latter, Figures 9 and 12, said enlarged portion 83 terminating at its lower end in a flange 84, the upper shoulder of which may form a convenient seat for the 35 rotary platen driver or gear 40, journaled upon said enlarged portion 83. The friction-bearing 47 may be pressed over the portion 81 of the stud after the gear 40 and ratchet-wheel 39 are in place. 40 For pivotally supporting the ratchet-wheel-pawl 38, the pawl-carrying arm 37 may be provided with a pivot-stud 86 projecting downwardly from said arm 37, as indicated in Figure 2. Said stud 86 may have a flange 45 87 to afford adequate seating against the arm 37 and to space the pawl 38 from said arm as indicated. The pawl may be retained upon the stud 86 by means of a washer 88, which may be riveted over the lower end of 50 the stud as indicated.

For rotation about its stud 53, the gear-sector 35 may have a hub 90, the lower end of which may bear upon a flange 91 of said stud 53. Said sector 35 may be retained by a 55 screw 92 threaded into the upper end of the stud 53.

The link 32, whereby the sector 35 is connected to the line-space lever 25, may be formed with a crook, as shown, to clear the 60 adjacent cam-groove-member supporting tab 73 when the mechanism is at its extreme operated position, as indicated in Figure 3. Said link 32 may be flat, and in order to secure the sector end thereof at the proper 65 level, said end may be pivotally connected to

a stud 93 secured to, and projecting upwardly from, the sector-arm 34. Said stud may be shouldered at its upper end to afford a pivot for said link which may be retained by a screw 94. The line-space-lever end of the link may 70 be retained in the space formed between the top of the slide 30 and the bottom of the cam-groove-member 62, as indicated in Figure 2, said space being determined by the height 75 of the cam-supporting tabs 73.

It will be apparent that for any given movement of the line-space lever 25, the resulting movement of the rotary platen driver or gear 40, and hence the platen 20, may be varied, 80 said movement of said gear and platen depending upon the distance of the pin 31 from the line-space-lever fulcrum, which distance in turn depends upon the adjustment of the cam-groove-member 62. By providing for different throws of the lever 25, different multiples of the line-space unit or basis established by the position of the pin 31 may be effected. For reasons which will presently become apparent, the line-space-effecting 85 stroke of said lever 25 is always terminated 90 with said lever in the same position. Consequently, for effecting different throws of the lever for different line-space multiples, the initial position of the lever 25 is varied according to the multiples desired. 95

Novel means whereby the initial position of the lever 25 is determined will now be described. A line-space-lever stop-arm, generally indicated by a number 96, may be fulcrumed around the lower end of the line-space-lever stud 45, so that a line-space lever-arresting abutment 97, forming part of said arm, may, in different positions of said arm, arrest said lever in different positions. Said abutment 97 may, as indicated, project upwardly from the forwardly-extending portion 98 of said arm to engage the side of the line-space lever. Said forwardly-extending stop-arm portion 98 may underlie the line-space-lever part 27 and be somewhat separated therefrom, as indicated, by a space 99. The fulcrum end 100 of said stop-arm may be bent downwardly from the forwardly-extending portion 98, as indicated, in order that it 105 may be fulcrumed about the lower end of the fulcrum-stud 45. The stop-arm 96 may be fulcrumed upon the portion 101 of said stud 45 included between the flange 84 and the surface of the plate 51 from which said stud 110 45 projects. For holding the stop-arm 96 in its different positions there may be provided notches 102 into which a projection 103 of the stop-arm 96 may be set, as best indicated in Figures 2 and 7. Said notches 102 115 may be formed in a segment 104, which may be secured as by screws 105 (Figure 10) to the upper surface of the plate 48 of the mounting 46. Said notches 102 are formed in the upper 120 surface of said sector, which upper sur- 125

face also supports the forward stop-arm portion 98 at the proper level.

By raising the stop-arm by its forwardly-extending portion 98, the projection 103 will 5 be lifted clear of the segment 104, and while said portion 98 is thus raised the stop-arm may be shifted to any position. Figure 8 indicates how the stop-arm portion 98 may be thus lifted, the stop-arm 96 tending to 10 tilt as a whole about a portion close to the fulcrum-stud 45, as indicated, and about another portion 106, with which the stop-arm may be provided to secure stability of said arm in any of its set positions. To secure 15 said stability, said portion 106 may be retained between the top and bottom sides of a groove 107 which may be formed in the segment 104. Said stabilizing portion 106 of the stop-arm 96 may be formed at the end of a 20 lateral extension 109, which may be bent downwardly from the stop-arm portion 98, to align said portion 106 with its retaining groove 107.

To assist in retaining the stop-arm in any 25 of its stop positions, there may be provided a spring 110 which may be secured to the bottom of the extension 109, as by rivets 111 (Figure 3). Said spring 110 may be provided with an end portion 112, which may 30 enter the groove 107, and the spring may be sprung so that said end portion 112, at all times, presses against the upper side of said groove 107, and by the reaction thus afforded the spring 110 tends to hold the forward stop-arm portion 98 against the locating segment 104. The space 99 between the stop-arm portion need only be sufficient to enable the stop-arm holding projection 103 to be lifted clear 35 of the segment 104. When the stop-arm is to be shifted, both the line-space lever and 40 the stop-arm are grasped between the fingers, and the forward stop-arm portion 98 is drawn upwardly toward the line-space lever to clear the segment 104 preparatory to shifting both the stop-arm 98 and the line-space 45 lever to the new position. The stop-arm may then be released so that the stop-arm projection 103 may settle into the proper slot 102, such settling of the projection into the slot 50 being facilitated by the spring 110. The portion 106 operates to stabilize the stop-arm in any of its different positions, by resisting the tendency of the stop-arm to turn over about the base of the stop-abutment 97, and 55 lift the projection 103 out of the slot 102 as the line-space lever bears against said stop-abutment.

The line-space stroke of the lever 25 may 60 be terminated with said lever always in the same position, by means of a fixed stop 113, which may be secured to and may project above the segment 104, so that the side of the line-space lever 25 may, at the end of the line-space stroke, strike said stop 113, as indicated 65 in Figure 3.

The stud 45, which affords the line-space-lever fulcrum and also affords other fulcrums for the mechanism, as explained, may be secured to the plate 51, from which it projects, by a screw 115, Figures 10 and 12. The lower end of said stud may terminate in a portion 116, which may enter and closely fit a hole in said plate 51, as indicated.

For preventing overthrow of the rotary platen driver or gear 40, and consequently of the platen at the end of the line-space stroke due to the tendency of the ratchet-wheel to continue its rotation after the stroke of the pawl is ended, there may be provided a stop which will not only arrest the pawl at a definite point at the end of the line-space stroke, but will also force the pawl against the ratchet-wheel to cause the pawl and ratchet-wheel to interlock and thereby positively hold the ratchet-wheel 39 as the pawl is arrested. For thus arresting the pawl and forcing it to interlock with the ratchet-wheel, the stud 77, against which the line-space-lever retracting-spring 69 reacts, may be utilized, and may serve to arrest the pawl in the manner indicated in Figures 3 and 4. It will be apparent from Figure 3 that the stud 77 may be located so as to force the teeth of the pawl and ratchet-wheel together as the pawl is arrested by said stud. The interlocking or forcing together of the pawl and ratchet-wheel teeth may be facilitated by providing the end of the pawl with a suitably inclined camming surface 118 to bear against the stud 77.

For determining the exact point at which the movement of the ratchet-wheel 39 is thus arrested by the stud 77, there may be provision for adjustment of said stud along the path of the pawl 38. To this end, a hole 119 in the mechanism-mounting plate 48 may be 105 elongated, a screw 120 passing through said hole to secure said stud. As the movement of the pawl and ratchet-wheel is arrested by a fixed stop, namely, the stud 77, and the line-space stroke of the lever 25 is also arrested by the fixed stop 113, the slot 29, wherein the slide 30 is guided for varying the length of the platen-driving arm of the line-space lever, must be concentric with the point at which the link 32 is pivoted to the gear-sector 35. That is to say, said slot 29 must be concentric with said point when the mechanism is in a position corresponding to Figure 3, in which the line-space lever is at the end of its line-space stroke. It will be seen that the slot 29 being thus concentric with the point 33, the slide 30 may be moved to any position while at the same time the pawl 38 may always be arrested by the stud 77.

Suitable details of the friction bearing 125 47 that retains the pawl-controlling ring 44 are illustrated in Figure 9, which includes a cross-sectional view of the assembled bearing and detail perspective views of the bearing and the ring 44. The bearing 130

47 may include a ring 121 having a shoulder 122 which may be overlapped by a ring 123; said rings being fastened together as by riveting a projection 124 from said shoulder 122 over the edge of the central hole of said ring 123. Thus there may be formed between said ring 123 and another shoulder 125 of the ring 121 the sides of a groove which has as its bottom the portion projecting from said shoulder 125. Said bottom of the groove may fit the central hole 126 of the ring 44 to retain the same concentrically with the central hole 127 formed in the ring 121 of the bearing. The ring 44 may be formed of thin material, as, for example, spring steel of a thickness not greater than the width of the groove in which said ring 44 is retained. The required frictional drag upon the ring 44 may be effected by warping, twisting or bending the ring, as suggested by the dot-and-dash lines 128, so that when said ring is assembled and pressed flat between the sides of the groove the tendency of the ring to warp again will cause the ring to rub against the sides of the groove to create the desired friction. For holding the assembled friction bearing in place, the central hole 127 may be a force fit over the stud 45 at the portion 81 of said stud.

30 If, for compactness of the mechanism, the rotary platen driver or gear 40 is lowered so that the portion of said gear, which engages the gear 55 in normal case position of the platen, is below the pitch line of the 35 bevel gear 57, the central portion 129 of said gear 55 may be elevated above said pitch line to afford room for the bevel pinion 56.

40 Figures 11 and 13 illustrate details of the speed-reducing train that connects the platen-driving gear 40, mounted on the type-writer-carriage, to the platen 20 carried in the platen support or case-shifting frame 22. The speed-reducing train and its mounting 60 are the only parts of the line-space organization carried by the platen-support, and the mounting may be arranged to hold the parts of the speed-reducing train in proper juxtaposition to one another, and also to secure proper engagement of said 45 train with the platen-driving gear 40 on the letter-feeding carriage. To this end, said mounting may include spaced-apart ears 130 which may fit over the platen-axle 21, so that the location of said mounting and speed-reducing train may thereby be definitely keyed to the platen-axle. Said ears 130 may extend downwardly from front-to-rear-extending cross-members 131 and 132, which may be joined by members 133 extending 50 parallel to the platen-axle. The cross-member 132, toward the platen support, may be formed in two parts, as best shown in Figure 13, one part having one of the ears 130 and also having an extension 134 projecting 55 toward the platen-support, the other part

being formed by bending the member 133, which, in turn, is formed by bending the cross-member 131. The opposite member 133 is also formed by bending the cross-member 131. From said other part of the cross-member 132 there may be bent a portion 135 to afford a bearing hole 136 for the lower end of the spindle 58. Said spindle 60 may have an upper bearing in a member 137, which, in order to be assembled as part of the mounting, may be extended to form portions 138 bent around the gear 55, so that its ends 65 may be secured to the cross-members 131 and 132 of the mounting in the manner indicated 70 in Figure 13. The frame-like structure thus formed by the member 137 and its extensions 75 also serves to brace the cross-members 131 and 132 against spreading or contracting.

The bevel gear 57 may have projecting from the tooth-face side thereof a hub 141, and from the opposite side a hub 142, and the ears 130 of the mounting 60 may straddle the opposite ends of the gear-hubs 141 and 142, as indicated in Figure 11, to thereby serve in 80 locating the mounting 60 longitudinally of the platen-axle. Said gear 57 may be keyed to the platen-axle 21, as by one or more set screws 143. There may also be provided collars 144 and 145 against which the outer sides 85 of said ears may bear. The collar 144 may be keyed to the platen-axle, as indicated in Figure 11, while the collar 145 may constitute the bearing in which the platen-axle is journaled. The extension 134 which projects towards the platen-support is for anchoring the mounting to said platen-support, and may be, to this end, provided with an ear 146 through which may pass a screw 147, for securing the mounting to a stud 148 projecting from the side of the platen-frame or support 22. In the illustrated form of the mounting 60 the several members thereof are formed of sheet-metal whose parts may be fastened together, as for example, by rivets 149. For insuring that the bevel gear 57 and bevel pinion 56 may at all times be held close enough to one another to avoid back lash, there may be provided a backing for said gear 57 which may brace said gear at a point opposite the bevel pinion 56. Said backing may be in the form of a block 150 which may bear against the back of the bevel gear 57 and thus aid in resisting any tendency of the reaction between said gear 57 and bevel pinion 56 to thrust the gear 57 away 110 from said pinion 56. The block 150 may also serve as a brake upon the platen to minimize the tendency to accidental displacement of the platen. To this end, said block 150 may bear with a suitable degree of friction upon the 115 back of the gear 57.

A hole 152, through which the screw 147 passes to secure the mounting 60 to the platen-frame 22, may be elongated, as indicated in Figure 13, so that the mounting may be rocked 120

about the platen-axle to thereby bring the gear 55 into proper mesh with the platen-driving gear 40 of the letter-feeding carriage. For direct rotation of the platen by hand, a 5 usual platen-rotating knob 153 may be secured to the end of the platen-axle beyond the line-spacing mechanism.

The plate 48 of the mounting 46 for the line-spacing mechanism on the carriage may 10 be opened out around the fulcrum-stud 45, as indicated at 154, so as to clear the gears 40 and 55 and afford clearance for the multiple-space stop-arm 96 and the shifting of said stop-arm. The line-spacing mechanism supported by said mounting may be covered by a 15 casing, generally indicated by the number 155, which may be arranged to expose only the cam-groove-member 62, and the handle portion of the line-space-lever part 27. A finger-piece 156 of the multiple-space stop-arm 96 may project beyond said casing for manipulation of said stop-arm 96.

For convenience of assembling the mechanism, the casing 155 may be formed in two 25 parts, a lower part 157 and an upper part 158. Said lower part of the casing may be in the form of a wall falling below and rising above the plate 48, as indicated, and reaching around said plate almost to the periphery of 30 the gear 55, see Figure 10. Said lower part 157 of the casing may be secured to the plate 48, as by solder applied around the joint between said part 157 and the plate 48, as indicated at 159, Figure 12. Upon the upper edge 35 of said lower part 157 of the casing, the upper part 158 of the casing may rest, the outline of said upper part, as viewed from the top of the casing, coinciding with the outline of the lower part. The upper part may include side 40 portions 160 forming said outline, and a mechanism-covering top-portion 161 having an opening to clear the cam-groove-member 62.

The stop-arm segment 104 may have a 45 number of slots 102 to position the stop-arm 96 for different multiples of line spacing, for example as shown herein, a single line space, and multiples of $1\frac{1}{4}$, $1\frac{1}{2}$, 2, $2\frac{1}{2}$ and 3 times said single line space, it being understood 50 that while the multiples might not be exact for all positions of the pin 31, the locations of the slots may be arranged, if desired, to secure a mean of the variations from exact multiples for different positions of the pin 55 31, and that thus said multiples may be exact enough for practical purposes.

The upper part 158 of the casing 155 may be secured by screws 166 which may be threaded into the plate 48, as indicated in Figures 5 60 and 6.

The cam-groove-member 62 and the clamping nut 72 therefor, may be provided with knurled finger-surfaces as shown at 167. The cam-groove-member 62 may also be provided 65 with graduations 168 spaced with any desired

degree of fineness and cooperating with a pointer which may be a mark 169 on the casing to serve as an index of the line spacing corresponding to the adjustment of said cam-member, it being understood that the 70 reading is to be taken when the line-space lever abuts the stop 113. The side of the upper part 158 of the casing may have an opening 170 to clear the gear-sector 35 and the stamping 26 of the line-space lever, as indicated at Figure 3.

For clearing the handle portion of the line-space lever, the front of the upper part 158 of the casing 155 may have an opening 163 extended sufficiently around said front 80 to accommodate the swing of the line-space lever. Along the upper edge of said opening there may be markings 164 spaced according to the different positions of the line-space lever corresponding to the different line-space 85 multiples. Said markings may co-operate with a pointer 165 on the line-space lever to indicate the line-space multiple for which the mechanism is set. The handle portion of the line-space lever may have at the end 90 thereof, as indicated in Figures 5 and 6, a finger-piece 162.

A casing may also be provided to enclose the speed-reducing train carried by the platen-support or frame 22, said casing being generally indicated by the number 171 and consisting of a top portion 172 and sides which may surround and cover the gear 55, the portion of the sides surrounding said gear being indicated at 173. The top portion and 100 side of the casing may be cut away, as indicated at 174, Figure 5, to clear the casing 155 on the carriage sufficiently to accommodate the case-shifting movement of the platen and its support or frame. Said speed-reducing train-casing 171 may be secured by screws 175 which may pass through the top portion 172 of the casing and be threaded into the platen-frame member 22, as indicated in Figures 5 and 6. The spindle 58 to which is 110 keyed the bevel pinion 56 may project through an opening 176 to a point where a finger-knob 177 attached to said spindle is conveniently accessible. Said finger-knob may, by enabling the spindle 58 to be rotated 115 thereby, be used for fine adjustment of the work-sheet on the platen to the printing line, said fine adjustment being effected by reason of the relatively large displacement of the spindle 58 as compared with a corresponding 120 displacement of the platen. The top portion 172 of the casing 171 may be elevated at a portion 179 (Figures 5 and 6) so that said latter portion may overlie and clear the gear-sector 35 and permit up-and-down case-shift- 125 ing movement of said casing 171. To also clear the end of said sector 35, the side of the casing 171 may be flared out as at 180 (see Figures 3 and 5).

The flange 70 of the line-space-lever ful- 130

crum-sleeve 63 may be a separate piece having a thread which fits the clamping nut thread of said sleeve. The lower flange 66 of said sleeve may be cut away where it would otherwise overlap the sides of the slide-guiding slot 29 in the line-space-lever stamping 26 which is seated against said lower flange. The sleeve 63 and stamping 26 are of course fastened together, as by solder or riveting not shown.

After the line-space-lever retracting-spring 69 is in place around the fulcrum-sleeve 63 of said lever, the flange 70 of said sleeve may be threaded over the upper sleeve 15 end to the proper level above the line-space-lever stamping 26, and secured against turning about said sleeve, as by solder, staking, or a key.

It will be noted that in the improved mechanism all the controlling parts, that is to say, all the parts which control the extent of movement of the rotary platen-driver or gear 40, are, including said gear 40, solidly supported by the letter-feeding carriage. Hence such controlling parts cannot be relatively displaced, nor, therefore, can they cause binding or lost motion as they resist the reactions set up in the operation of the mechanism. The points, about which the several controlling parts of the mechanism operate, are always maintained in proper relation to one another, and it is apparent that such might not be the case if such of the controlling parts as, for example, the equivalent of the platen-driving gear 40, the clutch and clutch-controlling mechanism, were carried by the shiftable platen-support which might be none too rigidly mounted, as often occurs in conventional typewriter-design.

Although the parts carried by the letter-feeding carriage are preferably assembled as a unit which may readily be attached to, or removed from, said carriage, as herein illustrated and described, it will be understood of course that instead of supporting said parts in a mounting 46, the mounting 46, and hence the unitary feature of the assembly, may be dispensed with, in which case the carriage-frame 23 itself may serve as such mounting, suitable provision being accordingly made in the form of the carriage-frame for the direct attachment thereto of those parts herein shown attached to the mounting 46.

As an illustration of different adjustments of the mechanism for different extents of line-spacing, reference may be had to Figures 1, 3 and 5. Figures 1 and 3 show the mechanism as adjusted for line space of maximum extent; that is to say, the grooved cam-member 62 (not shown in Figures 1 and 3) will have been turned to bring the pin 31 to its farthest distance from the line-space lever-fulcrum, the multiple space stop-arm 96 being set, as best shown in Figure 3, 65 in the farthest notch 102 from the fixed stop

113, said farthest notch corresponding to triple spacing of the line-space basis for which the pin 31 is adjusted. Figure 5, showing an illustration of a different setting of the mechanism, represents that the cam-groove-member 62 has been turned so that the pin 31 is at its minimum distance from the line-space lever-fulcrum, and that the stop-arm 96 is set in the notch corresponding to double spacing. It will be obvious that for each position of the stop-arm 96, the pin 31 may be micrometrically adjusted to any position within its range of movement by turning the grooved cam-member 62. Vice versa, regardless of the position of the pin 31, the stop-arm may be set into any of the notches 102. Thus the line-space extent may be micrometrically varied from a minimum of say one-tenth of an inch,—which minimum would correspond to an adjustment of the stop-arm 96, to the single-space notch, and of the pin 31 to its minimum distance from the line-space lever-fulcrum—to a maximum of say six-tenths of an inch, said maximum corresponding to the adjustment of the mechanism, as shown in Figures 1 and 3.

It will also be noticed that the line-spacing mechanism on the letter-feeding carriage is compactly arranged, and that the arrangement of the rotary platen-driver, clutch, clutch-controlling mechanism and line-space lever, all to operate about one fulcrum-stud, conduces to said compact arrangement.

It will be noted that the attachment may include two separate preassembled units, as 155 and 171, one unit 171 secured to the platen-shift-frame and the other unit 155 secured to the carriage, the two units becoming co-operative by the bringing together of the two gears 40 and 55 for a concomitant train of 105 mechanism intermediate the line-space lever and the platen.

Variations may be resorted to within the scope of the invention, and portions of the improvements may be used without others.

Having thus described my invention, I claim:

1. In a typewriting machine, the combination with a revoluble platen, a letter-feeding carriage and a shiftable platen-support carried by said carriage and shiftable relatively thereto for ease shifting, of a reciprocating line-space lever fulcrumed on said carriage, a platen-driving-gear rotatably mounted on said carriage, means for rotating said gear carried by said carriage and solidly supported thereon, said gear-rotating means controlled by the line-space lever movement and having means so as to be effective to rotate said gear only in one direction of said lever-movement and ineffective in the reverse direction, and means, carried by the platen-support, connecting said gear and platen to effect line-spacing of the latter through rotation of said gear, said last-mentioned con-

necting means on the platen-support and the gear on the letter-feeding carriage having provision so as to be relatively shiftable in accordance with the case-shifting movement of the platen and its support.

2. In a typewriting machine, the combination with a revoluble platen, a letter-feeding carriage and a shiftable platen-support carried by said carriage and shiftable relatively thereto for case-shifting, of a reciprocatory line-space lever fulcrumed on said carriage, a platen-driving-gear rotatably mounted on said carriage, means for rotating said gear carried by said carriage and solidly supported thereon, said gear-rotating means controlled by the line-space lever movement and having means so as to be effective to rotate said gear only in one direction of said lever-movement and ineffective in the reverse direction, and means, carried by the platen-support, connecting said gear and platen to effect line-spacing of the latter through rotation of said gear, said gear-rotating means also having provision to permit independent rotation of the platen in any direction.

3. In a typewriting machine, the combination with a revoluble platen, a letter-feeding carriage and a shiftable platen-support carried by said carriage and shiftable relatively thereto for case shifting, of a reciprocatory line-space lever fulcrumed on said carriage, a platen-driving-gear rotatably mounted on said carriage, means for rotating said gear carried by said carriage and solidly supported thereon, said gear-rotating means controlled by the line-space lever movement and having means so as to be effective to rotate said gear only in one direction of said lever-movement and ineffective in the reverse direction, settable means for limiting the displacement of the gear-rotating means to different extents for different line-space multiples, and means, carried by the platen-support, connecting said gear and platen to effect line spacing of the latter through rotation of said gear.

4. In a typewriting machine, the combination with a revoluble platen, a letter-feeding carriage and a shiftable platen-support carried by said carriage and shiftable relatively thereto for case shifting, of a reciprocatory line-space lever fulcrumed on said carriage, a platen-driving gear rotatably mounted on said carriage, means for rotating said gear carried by said carriage and solidly supported thereon, said gear-rotating means controlled by the line-space lever movement and having means so as to be effective to rotate said gear only in one direction of said lever-movement and ineffective in the reverse direction, said gear-rotating means also having provision whereby the extent of rotation of said gear, as derived from a given movement of said lever, may be micrometrically varied at will, and means, carried by

the platen-support, connecting said gear and platen to effect line-spacing of the latter through the rotation of said gear.

5. In a typewriting machine, the combination with a revoluble platen, a letter-feeding carriage and a shiftable platen-support carried by said carriage and shiftable relatively thereto for case shifting, of a reciprocatory line-space lever fulcrumed on said carriage, a platen-driving-gear rotatably mounted on said carriage, means for rotating said gear carried by said carriage and solidly supported thereon, said gear-rotating means controlled by the line-space lever movement and having means so as to be effective to rotate said gear only in one direction of said lever-movement and ineffective in the reverse direction, said gear-rotating means also having provision whereby the extent of rotation of said gear, as derived from a given movement of said lever, may be micrometrically varied, at will, and means, carried by the platen-support, connecting said gear and platen to effect line spacing of the latter through the rotation of said gear, said last mentioned connecting means on the platen-support and the gear on the letter-feeding carriage having provision so as to be relatively shiftable in accordance with the case-shifting movement of the platen and its support.

6. In a line-spacing mechanism for a revoluble typewriter-platen having a case-shifting platen-support carried by a letter-feeding carriage, the combination with a reciprocatory line-space lever mounted on said carriage, of a rotary platen-driver mounted on said carriage, means carried by said carriage whereby reciprocation of said lever causes unidirectional line-space-effecting rotation of said driver, said means including provision whereby the extent of rotation of said driver is substantially greater than the required platen-rotation, to thereby minimize the force with which said driver may react upon said platen-support, and a speed-reducing device carried by the platen-support, whereby the large rotation of said driver is translated into platen-rotation of line-space extent.

7. In a line-spacing mechanism for a revoluble typewriter-platen, the combination with a letter-feeding carriage, a platen-mounting, and spaced-apart platen-supports for said mounting carried by said carriage and movable for case-shifting, of a reciprocatory line-space operator mounted on said carriage, a rotary platen-driver mounted on said carriage, means carried by said carriage whereby reciprocation of said operator causes uni-directional line-space-effecting rotation of said driver, and a device carried by said platen-mounting, whereby said driver may rotate said platen for line spacing, said device and driver being arranged so that the

force of reaction between them, as the platen is rotated, is substantially in a direction in which said mounting-supports are spaced apart.

- 5 8. In a line-spacing mechanism for a revoluble typewriter-platen, the combination with a letter-feeding carriage, a platen-mounting, and spaced-apart platen-supports for said mounting carried by said carriage
 10 and movable for case-shifting, of a reciprocatory line-space operator mounted on said carriage, a rotary platen-driver mounted on said carriage, means carried by said carriage whereby reciprocation of said operator causes
 15 uni-directional line-space-effecting rotation of said driver, said means including provision whereby the extent of rotation of said driver is substantially greater than the required platen-rotation to thereby minimize
 20 the force with which said driver may react upon said mounting, and a speed-reducing device, carried by the platen mounting, whereby the large rotation of said driver is translated into platen-rotation of line-space
 25 extent, said device and driver being arranged so that said force is substantially in the direction in which said mounting-supports are spaced apart.
9. A line-space mechanism for a typewriting machine having a carriage and a shiftable platen-frame, said mechanism including two separate preassembled units, one unit secured to the platen-frame and including a train of gearing connected with the platen
 30 and beginning with a driven gear, and the other preassembled unit secured to the carriage and including a train of gearing beginning with a line-space lever and ending with a driving gear, the attachment of the two
 35 units to the carriage and platen-frame respectively bringing the driving gear of one train into engagement with the driven gear of the other train, for a concomitant translation of motion intermediate the line-space lever and the platen.

- 40 10. A line-space mechanism for a typewriting machine having a carriage and a shiftable platen-frame, said mechanism including two separate preassembled units, one unit secured to the platen-frame and including a train of reduction gearing connected with the platen and beginning with a driven gear, and the other preassembled unit secured to the carriage and including a train of multiplying
 45 gearing beginning with a line-space lever and ending with a driving gear, the attachment of the two units to the carriage and platen-frame respectively bringing the driving gear of one train into engagement with the driven
 50 gear of the other train, for a concomitant translation of motion intermediate the line-space lever and the platen.

- 55 11. In a line-spacing mechanism for a revoluble typewriter-platen having a case-shifting platen-support carried by a letter-feed-

60 ing carriage, the combination with a reciprocatory line-space lever mounted on said carriage and having a shiftable device forming a platen-driving arm whose length may be varied, of a rotary platen-driver mounted
 65 on said carriage, means carried by said carriage and connecting the variable platen-lever arm to said driver, whereby reciprocation of said lever causes uni-directional line-space-effecting rotation of said driver, said
 70 means including provision whereby the extent of rotation of said driver is substantially greater than the required platen-rotation, to thereby minimize the force with which said driver may react upon said platen-support, and a speed-reducing device carried by the platen-support, whereby the large rotation of said driver is translated into platen-rotation of line-space extent.

75 12. In a line-spacing mechanism for a revoluble typewriter-platen having a case-shifting platen-support carried by a letter-feeding carriage, the combination with a reciprocatory line-space lever mounted on said carriage, of a rotary platen-driver mounted on said carriage, means whereby the reciprocation of said lever causes uni-directional line-space-effecting rotation of said driver, said means including a reciprocatory gear-sector having an arm operatively connected to an
 80 arm of said lever, a pinion operatively connected to said sector and to said driver, said sector and pinion proportioned to effect greater rotation of said driver than the required platen-rotation, to thereby minimize
 85 the force with which said driver may react upon said platen-support, and a speed-reducing device carried by the platen-support, whereby the large rotation of said driver is translated into platen-rotation of line-space extent.

90 13. In a line-spacing mechanism for a revoluble typewriter-platen having a case-shifting platen-support carried by a letter-feeding carriage, the combination with a reciprocatory line-space lever mounted on said carriage, of a rotary platen-driver mounted on said carriage, means whereby the reciprocation of said lever causes uni-directional line-space-effecting rotation of said driver, said means including a reciprocatory gear-sector having an arm operatively connected to an arm of said lever, a pinion operatively connected to said sector and to said driver, said sector and pinion proportioned to effect greater rotation of said driver than the required platen-rotation, to thereby minimize
 95 the force with which said driver may react upon said platen-support, means whereby the relative length of said arms may be varied, at will, to thereby change the extent of rotation of the driver as derived from a given movement of said lever, and a speed-reducing device carried by the platen-support, whereby the greater rotation of said
 100 105 110 115 120 125 130

driver is translated into platen-rotation of line-space extent.

14. In a line-spacing mechanism for a revoluble typewriter-platen having a case-shifting platen-support carried by a letter-feeding carriage, the combination with a reciprocatory line-space lever, of a fulcrum for said lever fixedly mounted on said carriage, a rotary platen-driver arranged, for compactness of the mechanism, to rotate about the axis of said fulcrum, means, carried by said carriage, connecting said lever to said driver whereby reciprocation of said lever causes uni-directional line-space-effecting rotation of said driver, said means including provision whereby the extent of rotation of said driver is substantially greater than the required platen-rotation, to thereby minimize the force with which said driver may react upon said platen-support, and a speed-reducing device carried by the platen-support, whereby the large rotation of said driver is translated into platen-rotation of line-space extent.

15. In a line-spacing mechanism for a revoluble typewriter-platen having a case-shifting platen-support carried by a letter-feeding carriage, the combination with a reciprocatory line-space lever, of a fulcrum for said lever fixedly mounted on said carriage, a rotary platen-driver arranged, for compactness of the mechanism, to rotate about the axis of said fulcrum, means carried by said carriage, connecting said lever to said driver whereby reciprocation of said lever causes uni-directional line-space-effecting rotation of said driver, said means including a reciprocatory gear-sector operatively connected to said lever, a pinion operatively connected to said sector and driver, said sector and driver proportioned to effect greater rotation of said driver than the required platen-rotation, to thereby minimize the force with which said driver may react upon said platen-support, and a speed-reducing device carried by the platen-support, whereby the large rotation of said driver is translated into platen-rotation of line-space extent.

16. In a line-spacing mechanism for a revoluble typewriter-platen having a case-shifting platen-support carried by a letter-feeding carriage, the combination with a reciprocatory line-space lever, of a fulcrum for said lever fixedly mounted on said carriage, a rotary platen-driver arranged, for compactness of the mechanism, to rotate about the axis of said fulcrum, means, carried by said carriage, connecting said lever to said driver, whereby reciprocation of said lever causes uni-directional line-space-effecting rotation of said driver, said connecting means including a reciprocatory gear-sector operatively connected to said lever, a fulcrum for said gear-sector carried by said carriage

and spaced from the line-space-lever fulcrum, a pinion meshing with said sector and for compactness of the mechanism, mounted for rotation about the line-space-lever fulcrum, said connecting means also including a clutch-device for operatively connecting said pinion and driver to effect said uni-directional rotation of the driver, said sector and pinion proportioned to effect greater rotation of said driver than the required platen-rotation, to thereby minimize the force with which said driver may react upon said platen-support, and a speed-reducing device carried by the platen-support, whereby the large rotation of said driver is translated into platen-rotation of line-space extent.

17. In a line-spacing mechanism for a revoluble typewriter-platen having a case-shifting platen-support carried by a letter-feeding carriage, the combination with a reciprocatory line-space lever, of a fulcrum for said lever fixedly mounted on said carriage, a rotary platen-driver arranged, for compactness of the mechanism, to rotate about the axis of said fulcrum, means, carried by said carriage, connecting said lever to said driver, whereby reciprocation of said lever causes uni-directional line-space-effecting rotation of said driver, said connecting means including a reciprocatory gear-sector operatively connected to said lever, a fulcrum for said gear-sector carried by said carriage and spaced from the line-space-lever fulcrum, a pinion meshing with said sector and, for compactness of the mechanism, mounted for rotation about the line-space-lever fulcrum, said connecting means also including a pawl and ratchet-wheel arranged for compactness of the mechanism, to rotate about the axis of the line-space-lever fulcrum, said pawl and ratchet-wheel connecting said pinion and driver to effect said uni-directional rotation of the driver, said sector and pinion proportioned to effect greater rotation of said driver than the required platen-rotation, to thereby minimize the force with which said driver may react upon said platen-support, and a speed-reducing device carried by the platen-support, whereby the large rotation of said driver is translated into platen-rotation of line-space extent.

18. In a line-spacing mechanism for a revoluble typewriter-platen having a case-shifting platen-support carried by a letter-feeding carriage, the combination with a reciprocatory line-space lever having a shiftable device forming a platen-driving arm whose length may be varied, and means whereby said device may be shifted and secured in any position, of a rotary platen-driver mounted on said carriage, a connecting train carried by said carriage, connecting said variable platen-driving arm to said driver, whereby reciprocation of said lever

causes uni-directional line-space-effecting rotation of said driver, and means carried by the platen-support connecting the driver to the platen.

5 19. In a line-spacing mechanism for a revoluble typewriter-platen having a case-shifting platen-support carried by a letter-feeding carriage, the combination with a reciprocatory line-space lever having a platen-driving arm, of a reciprocatory gear-sector having an arm operatively connected to said platen-driving arm, said sector mounted on said carriage, one of said arms having a shiftable device, whereby its effective length 10 may be varied, to thereby change the extent 15 of rotation of said sector as derived from a given movement of said line-space lever, means for micrometrically varying the position of said device and securing it in any 20 position, a rotary platen-driver mounted on said carriage, means, connecting said driver and sector, whereby reciprocation of said sector causes uni-directional line-space-effecting rotation of said driver, and means 25 carried by the platen-support connecting the driver to the platen.

20. A universal line-spacing mechanism for a revoluble typewriter-platen having a case-shifting support carried in a letter-feeding carriage, said mechanism including a rotary platen-driver rotatable about a bearing carried by said carriage for solid support, means carried by the platen-support, connecting said driver to said platen, and 30 means, also carried by the carriage for solid support, for rotating said driver step by step, at will, to line-space the platen in successive steps of line-space extent.

21. A universal line-spacing mechanism 40 for a revoluble typewriter-platen having a case-shifting support carried in a letter-feeding carriage, said mechanism including a rotary platen-driver rotatable about a bearing carried by said carriage for solid support, 45 means carried by the platen-support connecting said driver to said platen, and means, also carried by the carriage for solid support, for rotating said driver step by step, at will, to line-space the platen in successive steps of 50 line-space extent, said latter driver-rotating means having provision whereby the rotary steps of said driver are of substantially greater extent than the required platen-rotation, thereby to minimize the reaction of said 55 driver upon said platen-support, the aforesaid means operatively connecting said driver to said platen having provision whereby the large rotation of said driver is translated into platen-rotation of line-spacing extent.

60 22. In a line-spacing mechanism, the combination with a revoluble typewriter-platen, a carriage, a vertical fulcrum-stud on said carriage, and a reciprocatory line-space lever fulcrumed on said stud, of a rotary platen- 65 driver rotatable about said stud and positive-

ly geared with the platen, and a one-way clutch rotatable about said stud, said clutch having its driven member connected to said driver and its driving member connected to said line-space lever.

70 23. The invention as set forth in claim 22, in combination with clutch-controlling means operative to keep the driven and driving members of the clutch disengaged when the line-space lever is in its retracted position, to 75 permit independent rotation of the platen.

80 24. In a line-spacing mechanism, the combination with a revoluble typewriter-platen, a carriage, a vertical fulcrum-stud on said carriage, and a reciprocatory line-space lever fulcrumed on said stud, of a rotary platen-driver rotatable about said stud and positively geared with the platen, a one-way clutch rotatable about said stud, said clutch having its driven member connected to said 85 platen-driver and to a driving member connected to said line-space lever, and settable means on said stud effective to limit the stroke of the line-space lever to different extents for different line-space multiples.

90 25. In a line-spacing mechanism, the combination with a revoluble typewriter-platen, a fulcrum-stud spaced apart from said platen, a reciprocatory line-space lever fulcrumed on said stud, a rotary platen-driver rotatable about said stud and geared to the platen, a one-way clutch rotatable about said stud, said clutch having its driven member connected to said driver, and means connecting the driving member of the clutch to said line-space lever, said latter connecting means including a reciprocatory sector and a fulcrum for said sector having its axis spaced from the axis of the line-space-lever-fulcrum, said sector being geared to said driving member and having an arm connected to an arm of said lever.

95 26. The invention as set forth in claim 25, in combination with means for varying the relative lengths of the aforesaid arms of said sector and lever, to thereby vary the line-spacing rotation of said driver and platen as derived from a given movement of said lever.

100 27. In a line-spacing mechanism, the combination with a revoluble typewriter-platen, a fulcrum-stud spaced apart from said platen, a reciprocatory line-space lever fulcrumed on said stud, a rotary platen-driver rotatable about said stud and geared to the platen, a one-way clutch rotatable about said stud, 105 said clutch having its driven member connected to said driver, means connecting the driving member of the clutch to said line-space lever, said latter connecting means including a reciprocatory sector, a fulcrum for said sector having its axis spaced from the axis of the line-space lever fulcrum, said sector being geared to said driving member and having an arm, a link connecting said arm to an arm of said lever, and means for 110 115 120 125 130

varying relative lengths of said arms, to thereby vary a line-spacing rotation of said driver as derived from a given movement of said lever.

5 28. In a line-spacing mechanism, the combination with a revolute typewriter-platen, a fulcrum-stud spaced apart from said platen, a reciprocatory line-space lever fulcrumed on said stud, a rotary platen-driver rotatable about said stud and geared to the platen, a one-way clutch rotatable about said stud, said clutch having its driven member connected to said driver, means connecting the driving member of the clutch to said line-space lever, said latter connecting means including a reciprocatory sector, a fulcrum for said sector having its axis spaced from the axis of the line-space-lever fulcrum, said sector being geared to said driving member and having an arm, a link connecting said arm to an arm of said lever, one of said arms having a shiftable element for varying the length of said one arm, and means adjustable at will, and effective upon said element for shifting and securing the same in different positions, to thereby vary the line-spacing rotation of said driver and platen, as derived from a given movement of said lever.

29. In a line-spacing mechanism, the combination with a revolute typewriter-platen, a fulcrum-stud spaced apart from said platen, a reciprocatory line-space lever fulcrumed on said stud, a rotary platen-driver rotatable about said stud and geared to the platen, said lever having an arm of variable length embodied in an element shiftable toward and from the lever-fulcrum, an operating connection between said element and said driver, whereby reciprocation of said lever effects uni-directional line-space-effecting rotation of said driver, and a manipulatable device carried by said lever effective upon said shiftable element for changing, at will, and securing the position of said element, to thereby vary the line-spacing rotation of said driver and platen, as derived from a given movement of said lever.

30. In a line-spacing mechanism, the combination with a revolute typewriter-platen, a fulcrum-stud spaced apart from said platen, a reciprocatory line-space lever fulcrumed on said stud, a rotary platen-driver rotatable about said stud and geared to the platen, said lever having an arm of variable length embodied in an element shiftable toward and from the lever-fulcrum, an operating connection between said element and said driver, whereby reciprocation of said lever effects uni-directional line-space-effecting rotation of said driver, a manipulatable rotary cam carried by said lever and engaging said shiftable element for changing the position thereof, at will, to thereby vary the line-spacing rotation of said driver and said platen, as derived from a given movement of said lever,

and means for securing said cam, to thereby secure said element in its different positions.

31. In a line-spacing mechanism, the combination with a revolute typewriter-platen, a fulcrum-stud spaced apart from said platen, a reciprocatory line-space lever fulcrumed on said stud, a rotary platen-driver rotatable about said stud and geared to the platen, said lever having an arm of variable length embodied in an element shiftable toward and from the lever-fulcrum, an operating connection between said element and said driver, whereby reciprocation of said lever effects uni-directional line-space-effecting rotation of said driver, a manipulatable rotary cam carried by said lever, and for compactness arranged to rotate about the axis of the lever-fulcrum, said cam having a cam-surface which engages said element and ranges toward and away from said fulcrum so that by rotation of said cam said element may be shifted to vary the line-spacing rotation of said driver and platen, as derived from a given movement of said lever, and means for securing said cam, to thereby secure said element in its different positions.

32. In a variable line-spacing mechanism, the combination of a reciprocatory line-space lever having a shiftable element forming a mechanism-actuating arm of variable length, a fulcrum-stud for said lever, said lever having a hub bearing upon said stud, said hub extending beyond the body-portion of said lever, a cam-member designed for rotation concentrically about said hub and having a surface extending transversely of its axis of rotation, said surface having a cam-groove engaging said element so that said element may be shifted by rotating said cam-member, said lever having a seat for said cam-member disposed so that a space is formed between said cam-member surface and the body of said lever, said cam-member having a central hole larger than the diameter of said hub to form with said hub an annular space, and a lever-retracting spring retained within said space and having one portion connected to said lever, another portion of said spring projecting through the space formed, as aforesaid, between said cam-member surface and the body of said lever, said latter spring-portion projecting through said latter space for reaction against a suitable abutment external to said lever.

33. In a variable line-spacing mechanism, the combination of a reciprocatory line-space lever having a shiftable element forming a mechanism-actuating arm of variable length, a fulcrum-stud for said lever, said lever having a hub bearing upon said stud, said hub extending beyond the body-portion of said lever, a cam-member designed for rotation concentrically about said hub and having a surface extending transversely of its axis of rotation, said surface having a cam-groove

engaging said element so that said element may be shifted by rotating said cam-member, said cam-member having a central hole larger than the diameter of said hub to 5 form with said hub an annular space, the body-portion of said lever having projections whereon said cam-member is seated and whereby the aforesaid surface is spaced from the lever body-portion, said hub having 10 a flange forming a journal for the cam-member at a point substantially spaced from the body-portion of said lever, and a spring retained within the aforesaid annular space between said hole and hub, said spring having 15 one portion connected to said flange and another portion of said spring projecting through the space formed, as aforesaid, between said cam-member surface and the body-portion of said lever, said latter spring-portion projecting through said latter space 20 for reaction against a suitable abutment external to said lever.

34. The invention as set forth in claim 33, in combination with means for securing 25 the cam-member against accidental rotation relatively to the line-space lever.

35. In a line-spacing mechanism for a revoluble typewriter-platen, the combination with a reciprocatory line-space lever and a 30 rotary platen-driver connected to the platen, of connecting means, whereby reciprocation of said lever causes uni-directional line-space-effecting rotation of said driver, said means including a pawl having teeth co-operative 35 with complementary teeth on said driver, a reciprocatory arm on which said pawl is pivotally mounted to revolve about the axis of said driver, said arm being operatively connected to said lever and pawl-controlling 40 means for effecting the engagement and disengagement of said pawl, said pawl-controlling means including a fixed member having a surface extending substantially along the 45 path described by said pawl, said pawl designed for and having frictional connection with said surface effective to rotate said pawl about its pivot to cause it to engage the driver-teeth at the beginning of the advance stroke of the pawl-arm and to recede from the 50 driver-teeth at the beginning of the reverse movement of said arm, and a stop limiting the extent to which the pawl may recede from the driver-teeth, said pawl-controlling means effective to maintain the pawl in engagement 55 with the driver-teeth throughout the remainder of the advance stroke and effective to maintain said pawl out of engagement throughout the remainder of the reverse stroke, said pawl remaining out of engagement 60 at the end of said reverse stroke to permit independent rotation of said driver and platen.

36. In a line-spacing mechanism for a revoluble typewriter platen, the combination 65 with a rotary platen-driver having a circular

range of teeth, of a reciprocatory driving train for said driver, including an arm mounted for rotation about the axis of said driver, a pawl pivotally mounted on said arm and having a body-portion extending contiguous to the range of the aforesaid driver-teeth, said body-portion also having teeth normally disengaged from the driver-teeth and pawl-controlling means including a fixed member, a revoluble element retained in frictional connection with said member for revolution concentric with the driver-axis, said revoluble element connected to a point on said pawl outside of the pawl-pivot so that upon moving the pawl-arm the friction upon said rotary element is effective to rotate the pawl about its pivot and thereby cause it to engage the driver-teeth at the beginning of the advance stroke of the pawl-arm and to recede from the driver-teeth at the beginning of the reverse movement of said arm, and a stop limiting the extent to which the pawl may recede from the driver-teeth, said pawl-controlling means effective to maintain the pawl in engagement with the driver-teeth throughout the remainder of the advance stroke and effective to maintain said pawl out of engagement throughout the remainder of the reverse stroke, said pawl remaining out of engagement 95 to permit independent rotation of said driver and platen.

37. In a line-spacing mechanism for a revoluble typewriter-platen, the combination with a rotary platen-driver having a circular range of teeth, of a reciprocatory driving train for said driver, including an arm mounted for rotation about the axis of said driver, a pawl pivotally mounted on said arm and having a body-portion extending contiguous to the range of the aforesaid driver-teeth, said body-portion also having teeth normally disengaged from the driver-teeth and pawl-controlling means including a fixed member forming an annular guide concentric with the axis of said driver, a revoluble element frictionally retained in said guide, said revoluble element connected to a point on said pawl outside the pawl-pivot so that upon moving the pawl-arm the friction upon said rotary element is effective to rotate the pawl about its pivot and thereby cause it to engage the driver-teeth at the beginning of the advance stroke of the pawl-arm and to recede from the driver-teeth at the beginning of the reverse movement of said arm, and a stop limiting the extent to which the pawl may recede from the driver-teeth, said pawl-controlling means effective to maintain the pawl in engagement with the driver-teeth throughout the remainder of the advance stroke and effective to maintain said pawl out of engagement throughout the remainder of the reverse stroke, said pawl remaining out of engagement 110 to permit independent rotation of said driver and platen.

130

mit independent rotation of said driver and platen.

38. In a line-spacing mechanism for a revoluble typewriter-platen, the combination with a reciprocatory line-space operator, of a settable back stop-device for said operator for predetermining different line-space multiples, said device including an arm having a stop-abutment to arrest said operator at a retracted station, a fulcrum about which said arm may be swung for different retracted stations, and a member disposed adjacent the outer end portion of the stop-arm, said member having stop-arm-holding slots whose locations correspond to different retracted stations and into which a corresponding part of said end portion may be set, said end portion being releasable from said member preparatory to shifting the arm, by withdrawing it from said member in a direction transverse of the longitudinal extent of said arm and substantially parallel to the fulcrum thereof, said device also including provision whereby said arm is resiliently pressed and yieldably held in engagement with the formations of said member.

39. A multiple-space stop-device for a reciprocatory line-space lever operable about a fixed fulcrum, said lever having a handle-arm extending from said fulcrum, said device including a stop-arm swingable about the axis of said fulcrum, and having an outer end portion spaced from said handle-arm in a direction parallel to said fulcrum-axis, said end portion having a stop-abutment for said lever, and a member disposed adjacent said end portion having stop-arm holding formations whose locations correspond to different stop-stations and into which a corresponding part of said end portion may be set, said stop-arm having a stabilizing portion spaced from said abutment in a direction transverse of said arm, said stabilizing portion engaging said member to afford, in conjunction with the stop-arm end portion, a sufficient spread of bearing upon said member to stabilize said stop-arm as said lever reacts against said abutment, said stabilizing portion engaging said member in a manner to permit tilting of said stop-arm about a point of said member adjacent said stabilizing portion for withdrawing said end portion of the stop-arm from the holding formations of said member preparatory to shifting said stop-arm to different positions, said end portion being withdrawable toward the handle-portion of said line-space lever by gripping said end portion and handle portion together.

40. The multiple-space stop-device as set forth in claim 39, in combination with a resilient device attached to the aforesaid stop-arm and reacting against the aforesaid member to yieldably hold the aforesaid end portion against said member.

41. In a variable line-spacing mechanism

for a revoluble typewriter-platen mounted in a case-shiftable platen-frame carried by a letter-feeding carriage, the combination with a rotary platen-driver and operating means to intermittently rotate said driver step by step in one direction for line-spacing, said driver and operating means carried by said carriage for solid support, of a gear-train carried by the platen-frame for connecting said driver and platen, the step-by-step rotation of said driver being of substantially greater extent than the required line-space rotation of the platen, to thereby minimize the force of the reaction of said driver upon the platen-frame, said gear-train including a bevel-gear keyed to the platen and concentric therewith, a smaller bevel pinion meshing with said bevel-gear, and a larger spur-gear compounded with said bevel-pinion, said spur-gear meshing with said driver on the letter-feeding carriage, said gears and pinions proportioned to translate the greater rotation of said driver into platen-rotation of line-space extent.

42. The invention as set forth in claim 41 including, in combination, a platen-axle keyed to the platen and a mounting for said gear-train, said mounting having spaced-apart bearings upon the platen-axle between which the bevel-gear is retained, said bevel-gear being keyed to said axle and hence to the platen as aforesaid in claim 41, said mounting also having spaced-apart bearings aligned transversely of the platen-axle, and a spindle journaled in the latter bearings, the aforesaid bevel-pinion and the spur-gear compounded therewith being keyed to said spindle and definitely located by means of said latter bearings, said mounting being swingable about the platen-axle to adjust the large spur-gear toward or away from the rotary platen-driver.

43. The invention as set forth in claim 41 including, in combination, a platen-axle keyed to the platen and a mounting for said gear-train, said mounting having spaced-apart bearings upon the platen-axle between which the bevel-gear is retained, said bevel-gear being keyed to said axle and hence to the platen as aforesaid in claim 41, said mounting also having spaced-apart bearings aligned transversely of the platen-axle, and a spindle journaled in the latter bearings, the aforesaid bevel-pinion and the spur-gear compounded therewith being keyed to said spindle and definitely located by means of said latter bearings, said mounting being swingable about the platen-axle to adjust the large spur-gear toward or away from the rotary platen-driver, said mounting also having a surface bearing against the back of said bevel-gear at a point opposite the bevel-pinion to keep the teeth of said gear and pinion in proper mesh, said surface also affording a brake upon said platen by reason of its contact with the bevel-gear keyed to said platen.

44. The combination with a revoluble platen, of a bevel-gear connected thereto and concentric therewith, a relatively small bevel-pinion meshing with said platen-gear and having a finger-wheel for effecting slow rotative adjustment of the platen, a relatively large drive-gear fixed to said pinion, a reciprocatory line-space lever, a movement-multiplying train of mechanism operated by said lever and extending to said relatively large drive-gear to line-space the platen, and means for effecting minute variations in the extent to which said relatively large drive-gear is driven by said train of mechanism.
45. Line-spacing mechanism for a revoluble platen for a typewriting machine including, in combination, a large bevel gear having a rigid connection to the platen, a small bevel pinion having a vertical shaft and meshing with said gear, said pinion surrounded by a thumb-wheel, whereby the platen may be rotated at slower angular speed than said thumb-wheel, a ratchet-wheel having teeth of minute pitch and connected for driving said pinion, and a lever having a connection for driving said ratchet-wheel, said connection being variable to effect minute adjustment of the length of the line-space unit, and regulating means for determining the number of units of platen-spacing effected by the stroke of said lever; the pinion-axis intersecting the platen-axis.
46. Line-spacing mechanism for a revoluble platen for a typewriting machine including, in combination, a gear-train for rotating the platen, said train including a ratchet-wheel having minute teeth for driving said platen, and a lever having a connection to drive said gear-train, said connection being variable to effect minute adjustment of the length of the line-space unit, and space-regulating means including a lever pivoted concentrically with said line-space lever, said regulating lever having a stop engageable by said line-space lever for limiting the return stroke of the latter, a multi-notched device to co-operate with said regulating lever, and means whereby said regulating lever may be selectively located and detained by means of said notched device.

FRED WALSLEBEN.
